UNITED STATES PATENT OFFICE.

CHARLES E. DUNCAN, OF JOHNSTOWN, PENNSYLVANIA.

REGENERATING-FURNACE.

1,283,117.

Specification of Letters Patent.

Patented Oct. 29, 1918.

Application filed February 10, 1917. Serial No. 147,949.

To all whom it may concern:

Be it known that I, CHARLES E. DUNCAN, residing at Johnstown, in the county of Cambria and State of Pennsylvania, a citizen of the United States, have invented or discovered certain new and useful Improvements in Regenerating-Furnaces, of which improvement the following is a specification.

10 The invention described herein relates to certain improvements in regenerating chambers for furnaces. It has heretofore been customary to fill the gas and air chambers with an uninterrupted mass or body of checker work which is supported by tiles forming alternately the entrance and exit flues of the chambers. The products of combustion carry with them a more or less soot, dust, etc., which are deposited in the 15 checker work, as the products of combustion flow outwardly from the heating chamber through the checker work, thereby reducing the areas of the openings in the checker work, with a consequent loss of 20 efficiency. It has been the practice to remove the clogging deposits by directing air under pressure through the chambers, but these blasts of air simply shifted the clogging material from one portion of the 25 checker work to another.

The object of the invention described herein is to provide pockets or unobstructed 30 passages into which the dust, soot, etc. can be forced by the air blasts, and from which 35 they can be withdrawn. The invention is hereinafter more fully described and claimed.

In the accompanying drawing forming a part of this specification, Figure 1 is a 40 section plan view of the regenerating chambers of a furnace, having checker work embodying the improvement claimed herein and Fig. 2 is a sectional elevation of the same, the plane of section being indicated 45 by the line II—II, Fig. 1.

In the practice of the invention, bricks forming the checker work are arranged in

the usual or any suitable manner, the mass of brick work being supported as usual by the tiles 2 which are spaced apart so as to 50 form flues for the inflowing gas and air, and the outlet flues for the products of combustion. In arranging the bricks forming the checker work, pockets or vertical passages 3 are formed, said pockets extending 55 vertically and horizontally through the entire mass of brick and arranged in line with the openings 4 formed in the outer walls of the chambers for the removal of dust, carbon, etc., and for replacing the checker 60 work or portions thereof. When forcing air under pressure through the checker work, the air will take the path of least resistance, which will be toward these pockets, so that the dust and soot will be carried 65 thereinto in lieu of being shifted merely from one portion of the checker work to another. In case it should become necessary, the bulk heads formed in the openings 4 can be broken out and the soot and dust 70 removed from the pockets or passages 3.

I claim herein as my invention:

1. A regenerating chamber for furnaces having the checker work built up in a plurality of sections such sections being spaced 75 distances apart to form between adjacent sections vertical unobstructed passages extending through the checker work down to the flues underlying the checker work.

2. A regenerating chamber for furnaces 80 having the checker work built up in a plurality of sections such sections being spaced distances apart to form between adjacent sections vertical unobstructed passages extending through the checker work down to 85 the flues underlying the checker work, and openings in the walls of the chamber in line with the passages formed between sections.

In testimony whereof, I have hereunto set 90 my hand.

CHARLES E. DUNCAN.

Witness:

KATHERINE O. STATLER.
